Application February 23, 1934, Serial No. 712,508
Renewed July 3, 1936

4 Claims. (Cl. 230—191)

This invention relates to improvements in compressors particularly adapted to be used in refrigerating systems.

It is among the objects of the present invention to provide a compressor, preferably of the two-stage type, which is adapted to provide greater volumetric and also greater overall efficiency in a refrigeration system.

A further object of the present invention is to provide a compressor so constructed and arranged as to prevent undesirable circulation of lubricating oil throughout the refrigerating system which, in most instances, is caused by the foaming of the oil due to rapid vapor pressure changes in the atmosphere contacting the lubricating oil.

A still further object of the present invention is to provide a compressor of simple structure and compact design adapted to operate efficiently with comparatively low power requirements to drive it.

Further objects and advantages of the present invention will become apparent as the description of the accompanying drawing progresses, said drawing illustrating a preferred embodiment of one form of the invention.

In the drawing:

Fig. 1 is a longitudinal sectional view of a multi-cylinder compressor.

Fig. 2 is a transverse sectional view of the compressor, taken substantially along the line 2—2 of Fig. 1. Certain parts of the machine are shown in elevation for the sake of clearness.

Referring to the drawing, the numeral 10 designates the crankcase of the machine, which crankcase provides the cylinders 11, 12 and 13. The crankcase is open at the bottom, this opening being normally closed by the bottom pan 14, having suitable gaskets to prevent fluid leaks. At opposite ends of the crankcase lugs 15 and 16 are provided, respectively, which lugs are bored out to provide bearings in axial alignment and in which the crank-shaft 17 is journalled. The bore in lug 15 does not extend to the outside of the crankcase and thus requires no seal, however, the bore in lug 16 extends through its entire length so as to permit one end of the crank-shaft 17 to extend outside the casing 16 to permit attachment of the driving element (not shown). Any suitable seal 18 is provided between the shaft 17 and lug 16 so as to prevent fluid or gases from leaking from the crankcase at this point.

Fins 19 are provided on the cylinder portion 55 of the casing for strengthening the structure and

for dissipating heat generated at these points. Cylinders 11 and 13 may be termed "first stage compression cylinders" and the one designated by the numeral 12 may be termed the "second stage compression cylinder". In the present instance two first stage compression cylinders are shown, but it is obvious that only one is necessary to cooperate with the second stage cylinder. Each cylinder 11, 12 and 13 has a reciprocative piston 21, 22 and 23, respectively. Each of these pistons has a port or passage in its head portion and each port is provided with a control valve. Inasmuch as pistons 21 and 23 are alike, only one will be described detailedly.

The port in the head of piston 21 is designated by the numeral 24. This port consists of a plurality of openings arranged about a central web 25. An annular ridge or projection 26 on the inner surface of the piston head surrounds the port 24, said ridge providing a valve-seat adapted to be engaged by the disc-valve 27. This valve is normally, yieldably urged into engagement with the seat 26 by a spring 28 abutting against the head of screw 29 threaded into the web 25. The usual wrist pin is provided in the piston 21 providing for the attachment of the connecting rod 30. For purposes of description of the operation of the device, the port of piston 23 is referred to by the numeral 31, the valve by numeral 32 and the connecting rod of this piston is designated by the numeral 33.

The piston 22, in the second stage compression cylinder 12 has a port 35 in its head portion, similar to the ports in pistons 21 and 23. In the piston 22, however, the annular ridge 36, providing a valve-seat for valve 37, is on the outer surface of the piston head instead of the inner surface as in the case in pistons 21 and 23. An apertured plate 38 is secured to the outer surface of the piston head 22 in such a manner that said plate is normally spaced from the valve 37 when it is in engagement with its valve-seat 36, thus permitting the movement of the valve from its seat, still preventing improper displacement of the valve from the piston.

The crank shaft 17 has three eccentrically arranged discs 41, 42 and 43 in the present instance arranged 120 degrees apart, which discs form throws for the several connecting rods. A ring-shaped end 46 on rod 33 fits upon the disc 41, a similar ring-shaped end 45 on rod 39 fits upon disc 43 and the ring-shaped end 44 of rod 30 fits upon disc 42.

An oil well 50 with ducts 51 leading therefrom is provided in the lug 16 within the crank-case 55

and a similar oil well 52 with ducts 53 leading therefrom is provided in the lug 15 within the crank-case. These provide for the delivery of lubricating oil to the two bearings of the crank-shaft 17.

The numeral 60 designates the cylinder head of the compressor attachable to the cylinder block or casing 10 in any suitable manner. This cylinder head provides three separate chambers 61, 62 and 63. Chambers 61 and 63 are in communication with the respective cylinders 11 and 13 while chamber 62 is in communication with the cylinder 12. Port 64, in the cylinder head block 60 connects cylinder 11 with chamber 61 and a similar port 65 connects cylinder 13 with chamber 63. Valves control the flow of fluid through these ports 64 and 65, and inasmuch as both valve structures are alike, only one will be described for the sake of brevity.

Referring to Fig. 1, port 64 is shown having an annular ridge 66 which provides a valve-seat for the valve 67 which is normally, yieldably urged against this seat by a spring 68 interposed between a wall of chamber 61 and an abutment collar 69 secured to the end of the stem of valve 67. For the sake of description of operation, the similar valve of cylinder 13 is designated by the numeral 70 and its spring 71.

Both chambers 61 and 63 are connected to a common suction line 72 through suitable nipples 73, couplings 74 and pipes 75. Chamber 62, however, is in communication with a discharge conduit 76. The port 80 which connects cylinder 12 with chamber 62 is normally closed by any suitable valve mechanism which must be opened by pressure within the cylinder 12. In the drawing this valve is shown as being a flexible blade 81 anchored at one point to the cylinder head by a screw 82. A spring 84 interposed between the blade 81 and a bracket 83 secured to the cylinder head, assist the blade 81 in normally closing the port 80.

The structure of the device having been described detailedly, its operation will now be explained.

When the power element, not shown, but adapted to be attached to shaft 17, is rotating said shaft, pistons 21, 22 and 23 are reciprocated in their respective cylinders. As the pistons 21 and 23 are moved downwardly, toward the shaft 17, the resultant displacement of the pistons creates a lower pressure in the respective cylinders than exists in the suction line 72, thereby causing the respective valves 67 and 70 to be moved from their seats against the effect of their springs 68 and 71 respectively. This results in fluid being drawn from the suction line 70 through the pipes 75, couplings 74 and nipples 73 into the respective chambers 61 and 63 and thence through the now open ports 64 or 65 respectively. It will of course be understood that due to the angular relation of the two crank-shaft throws 41 and 42 the suction cycles of the two pistons 21 and 23 are not concomitant but successive, thus fluid will flow into chamber 63 and from there into cylinder 13 at a different time during a cycle of compressor operation than when said fluid flows into chamber 61 and from there through port 64 into the cylinder 11.

The first stage of compression occurs when either piston 21 or 23 moves upwardly to compress the fluid previously drawn into their respective cylinders 11 and 13. The valves 67 and 70 of the said cylinders 11 and 13 will close when the suction strokes of the respective pistons in said

cylinders are completed. When the fluid in a cylinder is compressed to a predetermined degree the piston valve, valve 27 on piston 21, or valve 32 on piston 23, is actuated thus permitting the compressed fluid to escape from the cylinder, through the open piston port into the crank-case in which the lubricating oil for the compressor is stored. The piston valve closes the piston ports automatically when the piston reaches its extreme upper position or upper dead center. Downward movement of the piston repeats the suction or intake cycle thereof.

While the pistons 21 and 23 are being reciprocated in their cylinders, piston 22 is likewise being reciprocated in cylinder 12, the relative position and cycles of these pistons being controlled by the relative angular positions of their respective crank-shaft throws or eccentrics 41, 42 and 43. When the second stage pressure piston 22 moves downwardly, the pressure differential on the two sides of the piston head will cause the valve 37 in said piston to be moved to open the port 35, thus permitting the fluid under the first stage of compression within the crank-case, to flow into the compression chamber of cylinder 12. When piston 22 reaches its lowermost position, valve 37 will close port 35 in said piston. Now, as the piston starts on its upward journey it exerts pressure upon the fluid within the compression chamber of cylinder 12 which, when compression in said chamber has reached a predetermined degree, will cause valve 81 to be lifted and permit the compressed fluid in cylinder 12 to be discharged into the receiving chamber 62. Continued discharge of fluid under pressure into chamber 62 will force the fluid from said chamber through the discharge conduit which, in a refrigerating system, is connected to the condenser.

Pistons 21 and 23, being first stage compression pistons, will draw gases into the compressor cylinders and deliver said gases into the crank-case of the compressor under first stage compression. Thus the crank-case may be identified as a container of first stage compressed vapor or gas. The piston 22 takes its supply from this crank-case and delivers said supply of vapor under second stage compression to a chamber, which in a refrigerating system is connected with the condenser.

The casing thus provides a crank-case in which the reciprocating mechanisms of the pistons are housed, into which the vapors are discharged under first stage compression and from which said first stage compressed vapors are withdrawn to be compressed at the second stage for final delivery to the condenser of the refrigerating system. The crank-case is also the reservoir for the lubricant supply. Due to the fact that the lubricant supply is carried within the second stage compression chamber, its subjection to wide varying pressures and therefore its tendency to foam is materially reduced.

The advantages of applicant's compressor may readily be recognized by comparing its design, operation and efficiency with ordinary machines of the same class.

In the conventional refrigeration compressor, the capacity of the unit to absorb heat at low evaporator temperatures is a comparatively small fraction of the capacity to absorb heat at somewhat higher evaporator temperatures. For example, a unit produced by a large manufacturer and marketed in large volume has a B. t. u. capacity of approximately 1360 per hour with an evaporator temperature of 26 degrees Fahren-

heit, but when the unit is operated with an evaporator temperature of -12 degrees Fahrenheit, under the same atmospheric temperature conditions, the capacity of the unit is reduced substantially to 416 B. t. u. per hour. This loss in capacity is due primarily to the fact that the unit, when operating at the colder temperature, must have a compressor suction pressure considerably below atmospheric pressure, which results in the refrigerant vapors becoming rarefied, or less dense, and the weight of gas drawn into the compressor on the suction stroke of the piston is considerably less than that drawn into the compressor on the suction stroke when the refrigerant gas is dense, as is the case when operating at higher temperatures. This loss in capacity is therefore due to loss in volumetric efficiency of the compressor. While there are many types of refrigerants that may be used, some of which will produce low temperatures while operating under a suction pressure that is above atmospheric pressure, the general result is the same in each case; dense vapors give high volumetric efficiencies, and rarefied vapors give comparatively lower volumetric efficiencies, and there is not a great deal of difference in overall efficiencies obtained on conventional compressors due to the type of refrigerant used. This loss in volumetric efficiency is further augmented by the wide pressure differential between the suction pressure and the cylinder head pressure. Whatever volume of vapor that remains in the cylinder after the piston has traveled to the top of its stroke, which is due to clearance around the valves, and head clearance, is compressed to maximum head pressure at the end of each compression stroke, but remaining in the cylinder, must expand on each down stroke of the piston to a value at least equivalent in pressure to the suction pressure of the compressor before any additional charge can enter the cylinder to be compressed on the next stroke. Where the pressure differential is high between the high and low pressure side of the compressor, a greater movement of the piston is necessary to provide the necessary displacement for expansion of the gas remaining in the cylinder after the compression stroke has been completed; this movement of the piston does no useful work in drawing in a new charge, and represents a loss in both energy and displacement.

In my invention, the compressor is so designed as to insure that a very low pressure differential is always present between the low and high pressure sides of the suction, or first stage piston, in this way preventing the loss in volumetric efficiency and wasted power described in the previous paragraph.

With this arrangement, it is possible to make the compressor smaller and still do the same amount of work, since a much higher percent of complete volumetric efficiency is obtained.

Another means for reducing power required to operate the compressor in my design, is the application of vapor which has been compressed to the first stage, to the under side of the second stage piston, so that the pressure differential on the two sides of the second stage piston equals the final pressure minus the first stage pressure.

A further reduction in the power required to operate my compressor results from its smaller relative size and piston displacement to do a given amount of refrigeration. With every compressor there is a certain amount of friction which must be overcome in order to move the

parts at the operating speed, which might be termed "residual friction" and the total power required to operate the compressor is that necessary to overcome the residual friction, plus the power necessary to accomplish the compression of the vapor. In small compressors used for household refrigerators and small commercial installations, the residual friction sometimes requires more power than the useful load, and is always a high percentage of the total power requirements. By reducing the size of the pistons and also reducing the bearing loads on certain parts of the compressor in the present invention the residual friction load is appreciably lessened, thus reducing power requirements, and increasing the overall efficiency of the unit.

When compressors are used which are designed to draw the charge of vapor from the evaporator into the crankcase of the compressor and into the compression cylinder through piston valves, the compressor lubricating oil in the crankcase is subjected to rapid pressure changes when the compressor is started up after an "off" cycle. This causes the oil to give off quantities of refrigerant which have been absorbed during the "off" cycle when the crankcase pressure was increasing, and the oil foams violently and becomes frothy, and considerable quantities of the oil are carried through the piston valves, and must circulate through the condenser, receiver and evaporator before it can return to do useful work in the crankcase of the compressor.

With some compressor designs, the amount of oil that migrates through the system is so great as to deprive the compressor of proper lubrication, and cause stuffing box seal trouble. This is especially true where refrigerants that are miscible in oil in any ratio, are used.

My invention provides a means of preventing the oil in the crank-case from being subjected to evaporator suction pressures, thus preventing excessive foaming of the oil and the resultant migration thereof.

It may also be noted that by the use of my invention, the variations in torque effort throughout a single revolution of the drive shaft are materially reduced due to the fact that the work cycles for each of the pistons are staggered relative to the work cycles for the other pistons. In other words, the present design considerably smooths out the torque required to drive the compressor through a single revolution since the compression of gas in the second stage cylinder does not take place simultaneously with the compression of gas in the crankcase by the two first stage pistons.

In the accompanying drawing I have shown the compressor designed as a two-stage three cylinder compressor, but it is expressly understood that my application is not limited to the details of the design as shown; that any desirable number of cylinders may be used to accomplish the action described in this application, and any number of stages of compression may be used by the use of a web in the crank-case separating the stages used in excess of two, and sealed from the other crank-case compartments by means of stuffing box seals.

While the embodiment of the present invention as herein disclosed, constitutes a preferred form, it is to be understood that other forms might be adopted, all coming within the scope of the claims which follow.

What is claimed is as follows:

1. A multi-stage compressor comprising a first

stage compression section including at least one cylinder having an inlet check valve in the head thereof and an outlet, a second stage compression section including a cylinder having an inlet and an outlet, a crankcase communicating with the outlet from the first stage cylinder and with the inlet to the second stage cylinder, a drive shaft, means in said first stage cylinder for intermittently compressing fluid, means in the second stage cylinder for intermittently compressing fluid and means including separate connections between each of the compressing means and the drive shaft for staggering the work cycle of each compressing means with respect to each other compressing means.

2. A multi-stage compressor comprising a first stage compression section including at least one cylinder having an inlet check valve in the head thereof, a movable piston in said first stage cylinder, said piston having an opening therein constituting an outlet from said cylinder, a check valve for controlling said outlet, a second stage compression section including a cylinder having an outlet check valve in the head thereof, a piston in said second stage cylinder, said last named piston having an opening therein constituting an inlet to said second stage cylinder, a check valve for controlling said inlet to said second stage cylinder, a crankcase communicating with the outlet from said first stage cylinder and with the inlet to said second stage cylinder, a drive shaft, and means including separate connections between each of the pistons and the drive shaft for staggering the work cycle of each piston with respect to the work cycle of each other piston.

3. A multi-stage compressor comprising a plu-

rality of first stage compression chambers each having a valve controlled inlet and a valve controlled outlet, a second stage compression chamber having a valve controlled inlet and a valve controlled outlet, said compressor having a crankcase communicating with all the outlets of said first stage compression chambers and with the inlet to said second stage compression chamber, separate movable compressing means in each of said chambers, a drive shaft, and means including separate connections between each of the compressing means and the drive shaft for staggering the work cycle of each compressing means with respect to each other compressing means.

4. A multi-stage compressor comprising a first stage compression section including at least two cylinders each having an inlet check valve in its head, movable pistons in said cylinders, each piston having an opening therein constituting outlets from said cylinders, a check valve for each of said openings, a second stage compression section including a cylinder having an outlet check valve in the head thereof, a piston in said cylinder, said last named piston having an opening constituting an inlet to said second stage cylinder, a check valve for controlling said inlet to said second stage cylinder, a crankcase communicating with the outlets from all of said first stage cylinders and with the inlet to said second stage cylinder, a drive shaft, and means including separate connections from each of said pistons to said drive shaft for staggering the work cycle of each piston with respect to the work cycle of each other piston.

WILFORD H. TEETER. 35
